CIGARETTE PACKAGE CONTAINER AND SUPPORT

Costas George Rentos, Brooklyn, N. Y.

Application February 19, 1947, Serial No. 729,440

2 Claims. (Cl. 248—196)

1

This invention relates to cigarette package container and support, and has for one of its objects the production of a simple and efficient container for supporting a cigarette package in an upright position upon a table, desk and the like, in a manner whereby the cigarettes may be easily extracted from the package.

A further object of this invention is the production of a simple and efficient spring support for the package container for bracing the package container in an upright position.

Other objects and advantages of the present invention will appear throughout the following specification and claims.

In the drawing—

Figure 1 is a perspective view of the cigarette package support and container;

Figure 2 is a rear elevational view thereof with the top or cover in a closed position;

Figure 3 is a central vertical sectional view of the container, with the top in an open position;

Figure 4 is a transverse sectional view taken on line 4—4 of Figure 1, with the cigarette package removed.

By referring to the drawing, it will be seen that 10 designates the container which is preferably provided with a hinged top 11. The container 10 is provided with an inclined bottom 12 to rest upon a support while the container is supported in an inclined position, as shown in Figures 1 and 3. The container 10 is provided with a rear wall 13 in which is formed a vertical or longitudinally extending, centrally located, slot 14. A pair of vertically extending longitudinally extending ribs 15 are pressed outwardly from the rear wall 13 in parallel relation to define a channel 16 therebetween.

A brace 17, which is formed of spring metal is secured at its upper end to the container 10 within the channel 16 near the upper end of the container 10 and fits snugly between the ribs 15, to hold the brace 17 against lateral twisting movement. The upper end of the brace may be soldered, welded or secured to the container in any suitable manner common to the trade. The brace 17 is provided with a lower free end 18 and is provided with a longitudinal slot 19, which registers with the slot 14 formed in the container 10. A slide or button 20 extends through the slots 14 and 19 and this slide or button 20 overhangs the under or inner face of the edges of the slot 14 in the container and also overhangs the outer face of the slot 19 in the spring metal brace 17. As the slide or button 20 is moved downwardly to the position shown in Figure 2, the brace 18 will

2

be held flat within the channel 16 in the manner shown in Figure 4. When, however, it is desired to stand the container 20 upon a support, the button or slide 20 is moved upwardly of the slots 14 and 19 to the position shown in Figures 1 and 3 to the point where the brace 17 is secured to the container, and the lower free end 18 will automatically spring outwardly of the lower end of the channel 16 to a substantially vertical position. The brace 17 will then support the container 10 in an inclined position when the bottom 12 rests upon a support and the lower extremity of the brace 17 also rests upon a support as shown in detail in Figure 3.

15 It should be noted that as the button 20 is moved vertically of the container, the brace will automatically spring outwardly to a bracing position away from the container to constitute a support for the container. When the button 20 is moved downwardly, the spring brace 17 will be drawn to a position to lie flat against the container 10 within the channel 16 between the ribs 15. The side edges of the spring brace 17 will thereby be shielded and snugly encased between the ribs 17. The brace will then lie flush with the outer faces of said ribs.

When the cover or top 11 is open and the container is placed in the position shown in Figures 1 and 3, the cigarettes within the package 21, placed in the container, may be easily reached through the open top of the container. When the cover or top 11 is closed, the package 21 will be enclosed and protected within the container 10, and when the brace is moved to an inoperative position within the channel 16 by moving the button 20 downwardly, the container will accommodate itself in a pocket or other place of storage, without danger to the contents as well as surrounding objects or articles.

Having described the invention, what I claim is:

40 1. A device of the class described comprising a container, a brace carried by and secured to the container near the upper end thereof, the lower end of the brace being free, said brace being formed of spring metal, said container having a longitudinally extending slot formed in one wall thereof and located under the brace, said brace having a longitudinally extending slot formed therein and registering with the slot formed in the container, a slide extending through said slots, said slide overhanging the under face of the edges of the slot in the container and the outer face of the slot in the brace for moving said brace to a position to lie flat against said container when the slide is moved in one direction

45

50

55

and permitting the brace to spring outwardly away from the container when the slide is moved in the opposite direction to constitute a support for holding the container in an upright position.

2. A device of the class described comprising a container, a brace carried by and secured to the container near the upper end thereof, the lower end of the brace being free, said brace being formed of spring metal, said container having a longitudinally extending slot formed in one wall thereof and located under the brace, said brace having a longitudinally extending slot formed therein and registering with the slot formed in the container, a slide extending through said slots, said slide overhanging the under face of the edges of the slot in the container and the outer face of the slot in the brace for moving said brace to a position to lie flat against said container when the slide is moved in one direction and permitting the brace to spring outwardly

10

15

20

away from the container when the slide is moved in the opposite direction to constitute a support for holding the container in an upright position, and said container having a brace-receiving channel upon opposite sides of the slot which is formed in the container for encasing the brace therein when said slide is moved to a selected position to move the brace to an inoperative position.
